CLOTHESPIN

Harold K. Schultz, Brooklyn, and William F. Speagle, Berea, Ohio

Application September 10, 1937, Serial No. 163,288

2 Claims. (Cl. 24—137)

This invention relates to new and useful improvements in clothespins.

The primary object of this invention is to provide an improved form of clothespin which is capable of very tightly clamping clothes to a line by means of a double clamping action.

A further object of the invention is to provide a clothespin which is suitably shaped from a single strip of spring steel and is capable of 10 clamping clothes about a line at one point and clamping the folds of the clothes together at a point below the line.

Other objects and advantages of the invention will be apparent during the course of the following 15 description.

In the accompanying drawing forming a part of this specification and in which like numerals are employed to designate like parts throughout the same:

20 Figure 1 is an edge or side elevational view of the clothespin embodying this invention and illustrated in position to clamp clothes on a line;

Figure 2 is a side elevational view taken at right angles to Figure 1; and

25 Figure 3 is a horizontal transverse sectional view taken on line 3—3 of Figure 1.

In the drawing, wherein for the purpose of illustration is shown the preferred embodiment of this invention, the reference character 5 designates a section of a clothesline upon which the 30 piece of clothing is to be secured by means of the clothespin which is designated in its entirety by the reference character 7.

The clothespin embodying this invention is 35 formed from a strip or ribbon of spring steel of suitable width and gauge. This strip or ribbon is folded upon itself at 8 to provide the spaced converging arms 9. These arms 9 form the inner portions of the two sides of the clothespin body. One side is bent at 10, or at the outer end of the 40 arm 9, to provide a laterally offset, rearwardly directed fold 11 which is of substantially inverted U-shape. The opposite arms of this fold diverge downwardly, as best illustrated in Figure 1. The remaining arm 9 is bent laterally inwardly at 12 45 to provide an arm or branch 13 which underlies the mouth or entrance to the fold 11. Leg portions 14 are formed at the ends of the two sides of the body. Between the branch 13 and its leg 14, and angle 15 is provided and is positioned to 50 underlie the clothesline 5, as best illustrated in Figure 1. The legs 14 terminate in laterally flared extremities 16 which are rounded at their corners 17.

55 As this clothespin is formed of spring steel, its use in frosty, cold winter weather would have a tendency to cause the user's fingers to stick to the same. For that reason, the outside surfaces

of the strip or ribbon are provided with a relatively thin coating of rubber or latex, as illustrated in exaggerated section in Figure 3 and identified by the reference character 18.

In applying the clothespin to clothes positioned 5 upon a line, the pin is forced down over the clothing and line until the line with its surrounding portion of clothes is received in the inverted U-shaped fold 11. Due to the upwardly converging arrangement of the sides of this fold, the line 10 and clothes are wedged and tightly clamped together. This wedging action spreads the sides of the fold or places the fold under tension. Due to the positioning of the legs 14, they will clamp the material 6 at a zone beneath the line 5. This 15 clamping action results from placing the upper fold 8 under tension when the pin is forced down over the line. It will be appreciated, therefore, that the clamping of the clothes to the line results from tensioning the fold 11, and the clamping of 20 the clothes at a region or zone below the line results from tensioning the fold 8. It has been determined that the angle 15, formed between the branch 13 and the leg 14, very effectively cooperates with the opposed leg 14 for the other side of the pin to grip the clothing about the line. This 25 angle 15 also tends to more tightly grip the clothing when the wind blows.

It is to be understood that the form of this invention herewith shown and described is to be 30 taken as a preferred example of the same and that various changes in the shape, size, and arrangement of parts may be resorted to without departing from the spirit of the invention or the scope of the subjoined claims.

Having thus described the invention, we claim:

1. A clothespin of the type described comprising 35 a strip of spring steel formed with two sides arranged in opposed relation, one of said sides having therein a laterally offset rearwardly directed fold of substantially inverted U shape, a portion of the other of said sides being offset to underlie the entrance to said rearwardly directed fold, and said sides terminating in closely spaced parallel legs having outwardly flared ends. 40

2. A clothespin of the type described comprising 45 a strip of spring steel formed with two sides arranged in opposed relation, one of said sides having therein a laterally offset rearwardly directed fold of substantially inverted U shape, a portion of the other of said sides being offset to 50 underlie the entrance to said rearwardly directed fold, and said sides terminating in closely spaced parallel legs having outwardly flared ends and a thin coating of rubber applied to the outside surface of said strip. 55
